[57] CLAIM

The ornamental design for a boat chair, as shown and
described.

DESCRIPTION

FIG. 1 is a front perspective view of a boat chair showing
my new design;

FIG. 2 is a side elevational view thereof taken from one
side, the opposite side appearing as a mirror image;

FIG. 3 is a front elevational view thereof;

FIG. 4 is a top plan view thereof;

FIG. 5 is a rear elevational view thereof; and

FIG. 6 is a bottom plan view thereof.
